LOOM

Carl D. Brown, Hopedale, Mass., assignor to
Draper Corporation, Hopedale, Mass., a corpora-
tion of Maine

Application December 8, 1936, Serial No. 114,809

6 Claims. (Cl. 139—146)

The present invention pertains to fly shuttle looms, and has more particular reference to the shuttle picking mechanism of such looms.

Looms of the type to which my invention pertains commonly include a reciprocating lay, a picker stick carried by the lay, a cam shaft extending widthwise of the loom and having a pick cam revolving therewith in a vertical plane, and mechanism operated by the pick cam to impart the shuttle picking motion to the picker stick. The picking mechanism generally used prior to the present invention included a pick shaft of the vertical bell crank type positioned with its axis horizontal and at right angles to the cam shaft, one arm of the bell crank cooperating with the pick cam and the other arm thereof being connected to the picker stick through a lug strap. Such prior mechanism is subject to the disadvantage that the required angular relation of connected parts is conducive of inefficiency of the mechanism and causes considerable undesirable end thrust on the pick shaft and cam shaft.

An object of the present invention is to provide in a loom having a lay, picker stick and pick cam as aforesaid, a novel mechanism for transmitting motion from the pick cam to the picker stick, which mechanism shall include a pick lever positioned in the plane of the pick cam and a horizontal bell crank, having a vertical axis, so constructed and positioned as to operate efficiently and without undesirable end thrust.

The foregoing and other objects of the invention are conveniently accomplished in the preferred embodiment, herein disclosed. Such preferred embodiment is illustrated on the accompanying drawings, of which:

Fig. 1 is a view in elevation of a part of a loom to which the invention is applied;

Fig. 2 is a view in cross-section, taken approximately on line 2—2 of Fig. 1;

Fig. 3 is a view in cross section, taken approximately on line 3—3 of Fig. 1; and

Fig. 4 is a view, taken approximately on line 4—4 of Fig. 3, showing the picking mechanism with the pick cam turned slightly past picking position.

The loom shown on the drawings is of conventional construction except that it has applied to it the picking mechanism of my invention. Accordingly, the drawings show only such of the conventional parts of the loom as are necessary to an understanding of the present invention. Such conventional parts include the loom frame

of which the left hand loom side 1 is shown, a horizontal rocker shaft 2 on which the lay 3 is reciprocated as by a pitman 4 and crank 5, a picker stick 6 carried by the lay and having a picker 7 for engaging the shuttle 8, and the main cam shaft 9 which extends widthwise of the loom.

The lay reciprocates toward and from the front of the loom, which is toward the right on Fig. 1. The picker stick 6 is approximately vertical, it having however a forward and rearward movement with the lay and a pivotal picking movement in the plane of the lay as is well known in the art. At lower end of the picker stick is a suitable parallel mechanism 10 and a lug strap support 11 is fixed to the picker stick intermediate the ends of the latter. A lug strap 12 is operated as hereinafter described to pull the picker stick inwardly, i. e. toward the right, Fig. 2, and thus move the picker end of the stick 20 inwardly and thereby throw the shuttle along the lay. The lug strap 12, as shown, differs from lug straps heretofore used, in that it comprises a rigid link having a universal or ball-and-socket connection 13 with the lug strap support 11 and a similar connection 13' at the inner end of the link.

The lug strap 12, and thereby the picker stick, is operated by a novel mechanism including a bell crank lever 14 which is mounted for oscillation about an approximately vertical axis and is provided with approximately horizontal angularly related arms 15 and 16. The axis of oscillation of this bell crank is the axis of a stud 17 fixed in a stand 18. The stand 18 is suitably fixed to a supporting member 19 carried by the loom side 1. The stud 17 is positioned rearwardly from the plane of the lay 3 and picker stick 6, between the lay and the cam shaft 9, and also inwardly of the loom from the picker 40 stick.

The arm 15 of the bell crank lever 14 extends from the axis of the lever forwardly to the vertical plane in which the picker stick 6 moves and terminates at a point inwardly from the picker stick and below the level of the lug strap support 11 thereon. The arm 15 in oscillating about the stud 17 moves between the solid line position of Fig. 3 and the position represented by the dotted line a. In its mid-position, the arm is approximately normal to the plane of the picker stick, and the construction is such that the arm throughout its movement remains quite close to such normal position. It will be noted that the stud 17 as shown on the drawings is

inclined to the vertical, and the plane in which arm 15 moves is not quite horizontal, but is inclined slightly so that the end of the arm is always below the level of the lug strap support 11.

5 The arm 16 of the bell crank lever 14 extends from the hub of the lever inwardly, at a right angle to the arm 15. The arm 16 terminates at a point in front of, but below, the pick cam 20. The bell crank lever is oscillated by means engaging the arm 16 and operated by the pick cam. The pick cam revolves in a vertical plane, it being fixed to the cam shaft 9 in any usual manner.

10 The particular cam-operated means for oscillating the bell crank lever 14 shown on the drawings is not essential to the invention in some of its aspects. I do, however, prefer to use the particular means shown, which comprises a pick lever 21 and a link 22 positioned and operating substantially in the vertical plane containing the 15 pick cam.

15 The lever 21, as shown, oscillates on a horizontal axis which is parallel to the cam shaft 9. To this end the lever may be pivotally mounted on a stud 23 which is fixed in a bracket 24 on the 20 loom side 1. This lever has an upwardly and rearwardly extending cam follower arm 25 which engages the pick cam 20. The arm 25 may include a cam-engaging roller 26. The lever also has a depending arm 27 which is located in front 25 of the pick cam. The bracket 24 carries a bumper 28 which is engaged by a stop 29 on the arm 25 to limit overthrow of the pick lever.

20 The arm 16 of the bell crank lever 14 terminates substantially in horizontal alignment with 30 and in front of the lower end of the depending arm 27 of the pick lever. The link 22 therefore extends substantially horizontally and is at all times at least approximately at a right angle to both the arm 16 and the arm 27. The link is 35 connected to the lower end of the arm 27 by means of a suitable ball-and-socket connection 30 and is connected to the arm 16 by a similar connection 31.

35 The operation of the mechanism will be obvious and need not be described in detail. It is noted, 40 however, that connected parts of the mechanism are so related as to operate freely and efficiently without the undesirable end thrust and side thrust present in prior shuttle picking mechanisms.

45 Having fully disclosed the preferred embodiment of my invention, I claim:

50 1. A fly shuttle loom having a reciprocating lay, a picker stick carried by the lay, a pick cam 55 revolving in a vertical plane, a pick lever oscillating on a horizontal axis in front of said cam, said lever having a cam follower arm engaging said cam and a depending arm, a bell crank lever oscillating on an approximately vertical axis, said 60 bell crank lever having angularly related arms one of which extends approximately normal to the plane of movement of said pick lever and the other of which extends approximately normal to the plane of the picker stick, a link connecting 65 said depending arm with the first said arm of said bell crank lever, and a lug strap connecting the other arm of said bell crank lever with the picker stick.

70 2. A fly shuttle loom having a reciprocating lay, a picker stick carried by the lay, a pick cam revolving on a horizontal axis which extends widthwise of the loom, a pick lever positioned in the same vertical plane as said cam and oscillating on a horizontal axis parallel to the axis 75 of said cam, said pick lever having a cam follower

arm engaging said cam and a depending arm in front of said cam, a bell crank lever oscillating on an approximately vertical axis, said bell crank lever having angularly related arms one of which terminates substantially in horizontal alignment with the lower end of said depending arm and the other of which terminates approximately in the vertical plane of said picker stick, a link connecting said depending arm with the first said arm on said bell crank lever, and a lug strap connecting the said other arm of said bell crank lever with the picker stick.

75 3. A fly shuttle loom having a lay reciprocating on a horizontal rocker shaft, a substantially vertical picker stick carried by the lay, a lug strap support on said picker stick intermediate the ends thereof, a bell crank lever mounted for oscillation about an approximately vertical axis located inwardly and rearwardly from said picker stick, said lever having angularly related arms one of which extends forwardly from said axis and terminates at a point below the level of said lug strap support, a lug strap connecting the forward end of said arm with said lug strap support, and cam operated means, engaging the other arm of said bell crank lever, for oscillating said bell crank lever and thereby actuating said picker stick.

80 4. A fly shuttle loom having a lay reciprocating on a horizontal rocker shaft, a substantially vertical picker stick carried by the lay, a lug strap support on said picker stick intermediate the ends thereof, a cam shaft extending widthwise of the loom, a pick cam on said cam shaft, a bell crank lever mounted for oscillation about a vertical axis located between said lay and said cam shaft and inwardly from said picker stick, said lever having angularly related arms one of which extends forwardly from said axis and terminates at a point approximately in the plane of said 85 picker stick but inwardly from and below the level of said lug strap support, a lug strap connecting the forward end of said arm with said lug strap support, and means operated by said pick cam and engaging the other arm of said bell crank lever, for oscillating said bell crank lever and thereby actuating said picker stick.

85 5. A fly shuttle loom having a lay reciprocating on a horizontal rocker shaft, a substantially vertical picker stick carried by the lay, a lug strap support on said picker stick intermediate the ends thereof, a cam shaft extending widthwise of the loom, a pick cam fixed to said cam shaft and revolving in a vertical plane, a bell crank lever mounted for oscillation about a vertical axis located between said lay and said cam shaft and inwardly from said picker stick, said lever having angularly related arms one of which extends forwardly from said axis and terminates at a point inwardly from the picker stick but approximately in the plane thereof, a lug strap connecting the forward end of said arm with said lug strap support, the other arm of said bell crank lever extending inwardly of the loom from 90 said axis and terminating at a point in front of said pick cam, and means operated by said pick cam and engaging said other arm of said bell crank lever for oscillating said lever to thereby actuate said picker stick.

95 6. A fly shuttle loom having a lay reciprocating on a horizontal rocker shaft, a substantially vertical picker stick carried by the lay, a lug strap support on said picker stick intermediate the ends thereof, a cam shaft extending width-

wise of the loom, a pick cam fixed to said cam shaft and revolving in a vertical plane, a pick lever positioned in the same vertical plane as said cam and oscillating on a horizontal axis parallel to said cam shaft, said pick lever having a cam follower arm engaging said cam and a depending arm, a bell crank lever oscillating about a vertical axis located between said lay and said cam shaft and inwardly from said picker stick, said bell crank lever having an arm extend-

ing forwardly to a point inwardly from and below said lug strap support, said bell crank lever having another arm extending inwardly to a point substantially in horizontal alignment with the lower end of said depending arm, a link connecting said depending arm with said inwardly extending arm, and a lug strap connecting said forwardly extending arm with said lug strap support. 5
